(No Model.)

O. KRAUS.
BICYCLE BRAKE.

No. 595,106

Patented Dec. 7, 1897.

UNITED STATES PATENT OFFICE.

OTTO KRAUS, OF NEW YORK, N. Y.

BICYCLE-BRAKE.

SPECIFICATION forming part of Letters Patent No. 595,106, dated December 7, 1897.

Application filed November 16, 1896. Serial No. 612,191. (No model.)

To all whom it may concern:

Be it known that I, OTTO KRAUS, a citizen of the United States of America, and a resident of New York, in the county and State of New York, have invented certain new and useful Improvements in Brakes for Bicycles, of which the following is a specification.

My invention has reference to improvements in brakes for bicycles and other velocipedes, and has for its object to provide a brake-lever adapted to be attached directly to the handle-bar without the use of pins or pivots.

The nature of my invention will best be understood when described in connection with the accompanying drawings, in which—

Fig. 1 represents a plan or top view of a handle-bar provided with my improved brake-lever. Fig. 2 is a rear view, partly in section. Fig. 3 is a perspective, on an enlarged scale, of the locking-lug for holding the brake-lever within the handle-bar and for limiting its downward motion. Fig. 4 is a bottom view of a portion of the handle-bar. Fig. 5 is a vertical section taken through the lower end of the brake-plunger. Fig. 6 is a section in the plane 6 6, Fig. 5, drawn on an enlarged scale.

Similar letters and numerals of reference designate corresponding parts throughout the several views of the drawings.

Referring to the drawings, the letter *a* designates a tubular handle-bar provided with a post 1, fitted into the upper end of the fork stem or tube *b* and adapted to be secured by a suitable clamp *c*, all as usual. In the handle-bar and to one side of the post 1 are formed two diametrically opposite slots 2 and 3, adapted for the passage of the brake-lever *d*. Said lever has a handle 4, following substantially the curvature of the handle-bar and placed within reach of the hand and formed with an arm 5, which engages with its outer end the fork *i* of the brake-rod *e*, and said lever is also formed with an intermediate portion 6 at substantially right angles to the other two portions. Said intermediate portion is provided with an offset or shoulder 7 and with two bearing-surfaces 8 and 9. The bearing-surfaces 8 and 9 are adapted to contact, respectively, with the inner end of the slot 2 and with the bottom of the tube in

proximity to the outer end of the slot 3, while the shoulder or offset 7 forms a fulcrum about which the lever turns and the use of a pivot is dispensed with. The lower slot is made of a sufficient length to permit the lever to be passed through the handle-bar, and said slot is partially closed by any suitable device—such, for instance, as the locking-lug 10, made in I shape in cross-section, with a contracted neck 11 and with flanges 12 on opposite sides of said neck. The sides of the slot 3 are notched, as at 13 13, to permit the passage of the flanges of the locking-lug, said lug after insertion being slid toward the left of Fig. 4 to secure it in place. This locking-lug prevents the lever from falling out of the handle-bar and also serves as a stop to limit the outward motion of said lever. The brake-shoe *J*, of any usual construction, is attached to the lower end of the brake-plunger tube 17, which latter is prevented from turning by a longitudinal recess 14, formed in the same and engaged by a projection 16 on a disk 15, secured in the lower end of the fork-stem. The fork-stem is secured in any usual well-known manner into the steering-head tube *g*. The brake-shoe *J* may be readjusted when the handle-bar is raised or lowered by turning the threaded brake-rod *e* of the plunger. A spring *h*, acting on the disk 15 and on the plunger-head, normally holds the brake from the tire and the brake-lever away from the handle-bar.

It will be noticed that when the arm of the brake-lever is seated in the notch at the upper end of the brake-rod *e* the latter is prevented from turning, and consequently the position of the brake-shoe is immovably fixed with respect to the said brake-rod. In adjusting the brake to correspond to an adjustment in the height of the handle-bar the brake-lever is disengaged from the fork *i* of the brake-rod, so that the latter may be turned.

What I claim as new is—

1. A brake-lever formed with a handle, an arm and with an intermediate portion adapted to extend through the handle-bar tube and provided with an offset or shoulder forming a bearing adapted to contact with the inner surface of the handle-bar and with bearing-surfaces, substantially as described.

2. The combination with a handle-bar having oppositely-placed slots, of a brake-lever extending through said slots and provided with an offset or shoulder forming a fulcrum about which said lever turns, and with two bearing-surfaces engaging the inner end of the upper slot and with the bottom of the handle-bar tube and a brake placed in connection with the brake-lever, substantially as described.
3. The combination with a handle-bar having oppositely-placed slots, of a brake-lever extending through said slots and provided with an offset or shoulder forming a fulcrum about which said lever turns, and with two concentric bearing-surfaces engaging the inner end of the upper slot and with the bottom of the handle-bar tube, a locking-lug partially closing the lower slot and a brake placed in connection with the brake-lever, substantially as described.
4. In a velocipede, the combination of the handle-bar, the steering-head tube, the fork stem or tube, an adjustable brake-plunger provided with a longitudinal recess, a disk fitted to the fork-stem and provided with a projection engaging said recess, a brake-shoe attached to said plunger, and a brake-lever

extending through the handle-bar and engaging the upper end of the brake-plunger, substantially as described.

5. The combination with a tubular handle-bar having oppositely-placed slots, of a brake-lever extending through said slots and provided with a shoulder or offset forming a fulcrum, and with a concentric bearing-surface adapted to engage with the inner end of the upper slot, a locking-lug partially closing the lower slot, and a brake placed in connection with the brake-lever, substantially as described.

6. In a velocipede, the combination of a tubular handle-bar, a brake-lever passing through said handle-bar and having its fulcrum within the latter, a brake and a brake-rod having its upper end forked for the reception of the arm of the brake-lever, substantially as described.

In testimony that I claim the foregoing as my invention I have signed my name, in presence of two witnesses, this 3d day of October, 1896.

OTTO KRAUS.
